[57] **CLAIM**

The ornamental design for an identification member for a wrist bracelet, as shown and described.

DESCRIPTION

FIG. 1 is a top perspective view of an identification member for a wrist bracelet showing my new design;

FIG. 2 is a top plan view;

FIG. 3 is a side elevational view; and,

FIG. 4 is a front elevational view.

The rear of the identification member forms no part of the claimed design.

The broken line showing of a chain and clasp in FIGS. 1, 2 and 3 and of a chain in FIG. 4 are for illustrative purposes only and forms no part of the claimed design.
